(57) **CLAIM**

The ornamental design for an LED lighting panel, as shown and described.

DESCRIPTION

FIG. 1 is a perspective view of the LED lighting panel;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof, illustrating the LED lighting panel in use.

The broken lines shown are included for the purpose of illustrating environment and form no part of the claimed design.
